US00D616977S

(12) **United States Design Patent**
Asofsky et al.

(10) **Patent No.:** US D616,977 S
(45) **Date of Patent:** ** Jun. 1, 2010

(54) **FIREPLACE INSERT**

D224,224 S * 7/1972 Mango D23/335

(75) Inventors: **Mark Asofsky**, Delray Beach, FL (US);
Tyler Nemes, Boynton Beach, FL (US)

(Continued)

(73) Assignee: **Twin-Star International Inc.**, Delray Beach, FL (US)

FOREIGN PATENT DOCUMENTS

(**) Term: **14 Years**

CA 920111 1/1973

(21) Appl. No.: **29/328,882**

(Continued)

(22) Filed: **Dec. 3, 2008**

CA 920111 1/1973

(51) **LOC (9) Cl.** 23-03

Primary Examiner—Robert M Spear

(52) **U.S. Cl.** **D23/403**

Assistant Examiner—Karen Acker

(58) **Field of Classification Search** D23/331,

(74) Attorney, Agent, or Firm—James David Johnson, PA;

D23/335–341, 343, 344, 346, 350, 386, 387,
D23/390, 391, 393, 396–410, 415–421, 499;
D7/402, 407, 408, 335–337; 126/12, 13, 29,
126/44, 58, 92 AC, 144, 152 R, 215, 218,
126/219, 242, 243, 245, 500, 501, 509, 510,
126/544, 546, 548; 428/15, 21, 102; 431/125,
431/258, 268, 298, 302; 160/132, DIG. 9

James David Johnson

See application file for complete search history.

FIG. 1 is a front perspective view of a fireplace insert of the invention.

FIG. 2 is a front plane view of the fireplace insert of FIG. 1.

FIG. 3 is a left side view of the fireplace insert of FIG. 1.

FIG. 4 is a right side view of the fireplace insert of FIG. 1.

FIG. 5 is a top view of the fireplace insert of FIG. 1.

FIG. 6 is a bottom view of the fireplace insert of FIG. 1.

FIG. 7 is a rear view of the fireplace insert of FIG. 1; and,

FIG. 8 is a right front perspective view of the fireplace insert of FIG. 1.

The broken lines in the drawings represent unclaimed environmental subject matter.
